UNITED STATES PATENT OFFICE.

GEORGE A. SCHEHR, OF CINCINNATI, OHIO.

DESIGN FOR A DROP-HANDLE.

No. 37,935.

Specification for Design.

Patented April 3, 1906.

Application filed January 31, 1906. Serial No. 298,883. Term of patent 14 years.

To all whom it may concern:

Be it known that I, GEORGE A. SCHEHR, a citizen of the United States, residing at Cincinnati, Hamilton county, State of Ohio, have invented a new, original, and ornamental Design for a Drop-Handle, reference being had to the accompanying drawings, which show my design, Figure 1 being a front view, and Fig. 2 a side view, thereof.

I claim—

The ornamental design for a drop-handle as shown.

GEORGE A. SCHEHR.

Witnesses:

C. SPENGEL,
P. MEYER.
